CHING-CHIH YEE

Des. 157,554

PLATE OR THE LIKE

Filed Nov. 13, 1948

FIG. 2.

FIG. 1.

INVENTOR.
Ching-Chih Yee
BY Walter S. Fletcher

ATTORNEY.

UNITED STATES PATENT OFFICE

157,554

PLATE OR THE LIKE

Ching-Chih Yee, New York, N. Y., assignor to Castleton China Incorporated, New York, N. Y., a corporation of New York

Application November 13, 1948, Serial No. 149,619

Term of patent 14 years

(Cl. D44—15)

To all whom it may concern:

Be it known that I, Ching-Chih Yee, a citizen of China, residing at New York, in the county of New York and State of New York, have invented a new, original, and ornamental Design for a Plate or the like, of which the following is a specification, reference being had to the accompanying drawing, forming part thereof.

Fig. 1, is a plan view of a plate, showing my new design, and Fig. 2 is a side elevation thereof.

I claim:

The ornamental design for a plate or the like, as shown.

CHING-CHIH YEE.
